UNITED STATES PATENT OFFICE

FRED G. GROSS, OF CINCINNATI, OHIO

PIPE BENDING MACHINE

Application filed September 15, 1930. Serial No. 482,050.

This invention relates to a pipe bending machine, the primary object of the invention being to provide means whereby a pipe may be accurately bent or formed into a particular shape for a particular use.

An important object of the invention is to provide a device of this character having an adjustable bending member, to the end that pipes of various lengths may be bent by the device.

Another object of the invention is to provide means for bending a length of pipe, by a direct pressure exerted at a point intermediate the ends of the pipe, thereby insuring against the pipe bending too abruptly.

A still further object of the invention is to provide means whereby the device may be readily and easily clamped around a pipe section to be bent.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a pipe bending machine constructed in accordance with the invention.

Figure 2 is a plan view thereof.

Figure 3 is an end elevational view of the device.

Figure 4 is a sectional view taken on line 4-4 of Figure 1.

Figure 5 is a sectional view taken on line 5-5 of Figure 3.

Figure 6 is a sectional view through the central bending member.

Figure 7 is a sectional view taken on line 7-7 of Figure 2.

Figure 8 is an elevational view illustrating the removable section of one of the pipe clamps.

Referring to the drawings in detail, the device comprises a wheel supported base indicated generally by the reference character

5, the wheels on which the device is mounted being indicated by the reference character 6, and as shown are mounted at one end thereof.

Supporting legs 7 are secured at the opposite end of the base 5, the lengths of the legs 7 being such that the base 5 will be supported in a true horizontal plane at all times. Extending from the base 5 and disposed at opposite ends thereof, are supporting arms 8 that are supplied with bearings 9 disposed at the upper ends thereof, the bearings 9 providing supports for the shafts 10 that extend laterally from the curved pipe support 11. The curved pipe support 11 also includes a removable curved section 12 having lateral extensions 13 that are fitted in the sleeves 14 that are slidably mounted on the shafts 10, the sleeves being provided with spaced side members 15 between which the extensions 13 are positioned.

Keys 16 extend through openings in the side members 15 and overlie the upper edges of the extensions 13, to lock the section 12 of the pipe support in position, as shown by Figure 3 of the drawings. As before stated, these pipe supports 11 are disposed adjacent to the ends of the base 5, so that a pipe being bent may have its ends secured within the pipe supports and held in such position during the bending operation.

Eye bolts 17 are secured to the sections 12 of the pipe supports and afford means whereby the sections 12 may be readily and easily removed and replaced.

Arranged adjacent to the side edges of the base 5 are bars 18 which provide guides for the movable base 19 which is formed with curved recesses to receive the rollers 20 on which the base 19 is movably mounted. Chains 21 are secured at opposite ends of the movable base 19 so that the movable base may be moved longitudinally of the base 5. Extending upwardly from the movable base 19 is a cylinder 22 in which the piston 23 moves, the piston 23 having a head 24 that has its upper surface curved and grooved to provide a form or saddle over which the pipe under operation, is bent.

The head 24 is provided with a movable

section 25 which is hingedly connected to the lower portion of the head, a key 26 being provided for securing the movable section of the head in position around a pipe being bent.

5 At the lower end of the cylinder 22 is a pipe 27 through which air under pressure is directed to the cylinder to act on the piston to move the piston upwardly to bend the pipe held by the device.

10 From the foregoing it will be obvious that due to the construction shown and described, a pipe may be positioned with its ends in the pipe supports, a portion of the pipe being positioned on the head 24 and secured in position in a manner as described.

15 As air is forced into the cylinder 22, the piston 23 is forced upwardly, bending the pipe held by the device.

20 While I have shown and described the pipe supports of diameters to receive substantially large pipes, it is to be understood that removable sections may be positioned within the supports and head 24, the removable sections being of sizes to accommodate pipes of particular sizes, thereby adapting the machine for use in bending pipes of various diameters.

25 I claim:

30 1. A pipe bending machine comprising a base, upstanding arms secured to the base near the ends of the base, bearings at the upper ends of the arms, shafts disposed within the bearings and having curved central

35 portions to accommodate a pipe to be bent, removable curved members cooperating with the curved portions of the shaft for clamping the pipe in position, and means on the base for gripping the pipe intermediate the ends 40 of the pipe, to bend the pipe.

45 2. A pipe bending machine comprising a base, supporting arms at the ends of the base, bearings on the supporting arms, shafts having their ends disposed within the bearings

50 to pivotally support the shaft, said shafts having curved pipe receiving portions, disposed intermediate the ends thereof, a movable base on the first mentioned base, and means on the movable base for gripping and bending a pipe at a point intermediate its ends.

55 In testimony that I claim the foregoing as my own, I have hereto affixed my signature.

FRED G. GROSS.
